FOLDABLE BEACH LOUNGE

Jann W. Loken, Apt. 1503, Hotel Middletowne,
148 E. 48th St., New York 17, N.Y.

Filed Oct. 8, 1962, Ser. No. 72,015

Term of patent 14 years

(Cl. D15—11)

FIG. 3

FIG. 1

FIGURE 1 is a plan view of my foldable beach lounge in its fully opened, unfolded condition;

This application is a continuation in part of my now abandoned application D-64,728 filed April 13, 1961, entitled "Folding Beach Lounge."

The dominant features of my design for a foldable beach lounge reside in the portions shown in full lines and consist primarily in the configuration or particular shape of the blank taken together with the hinge or fold lines, all as shown.

I claim:

The ornamental design for a foldable beach lounge, substantially as shown and described.
